BELT-SUPPORTED PISTOL HOLDER

Sumner W. Adams, Visalia, Calif., assignor to
Allen A. Sanborn, Porterville, Calif.

Application May 18, 1954, Serial No. 430,510

2 Claims. (Cl. 224—3)

This present invention relates generally to the art of holsters for revolvers and pistols, and more particularly to the type of holster which is intended for attachment to, and to be chiefly supported from, a waist belt. This present holster has many of the characteristics of the holster shown in my U. S. Patent No. 2,577,869. It does, however, vary in certain details of structure which add immeasurably to the ease of manufacture, to a longer useful life, and permit a much more convenient use of the holster.

Present day conditions have indicated the increasing need for a holster to be used with either a revolver or an automatic pistol which will admit of having the same so mounted that it is reasonably concealed with an outer garment, and at the same time have it so arranged as to admit of a "fast draw." Despite the diverse stringent legislation among the various States relative to the use and carrying of hand guns, the recent war has clearly demonstrated the need of the hand gun and particularly one that can be kept largely concealed, but which can be drawn with safety, and quickly, during periods requiring its use. For the military personnel, the present day infiltration tactics employed in modern warfare have dispensed to a large degree with the fixed front line. Consequently the scene of combat has increased greatly in depth on the battle front and it now becomes incumbent upon the individual to be his own personal protector. This problem is greatly increased by the infiltration tactics and the ease with which an enemy may masquerade as of friendly population so that he gains close proximity to combat forces. When it is demonstrated he is truly an enemy, it is then forced upon each person to take over his own personal protection, and this must be done very quickly. These conditions have created a new technique for the use of hand guns and this present holster is ideally constituted to assist in solving this current problem. Another group that has need for an improved "fast draw" holster is the various law-enforcement agencies, many of whom, if they are to serve their purposes, dress in plain clothes. However even the uniformed enforcement officer is always faced with the public necessity of not using his firearms until all other means have failed, and then when the need becomes apparent, he must be able to go into action quickly. It therefore appears apparent that there is a great need for an improved present day holster of the type permitting concealment and a quick draw. It is to solve these problems of persons who in all propriety carry hand guns that I have provided this improved form of holster.

The principal object of this present invention is to provide a combat holster for hand guns which will insure the accurate and positive positioning of a hand gun so that it may be drawn quickly for use.

A further object of this invention is to provide a "quick draw" holster for hand guns which can be easily applied to, or removed from, a service belt without regard to the number of loops of appendages which may already be in place on the belt.

2

A further object of this invention is to provide an attaching means whereby a holster can be quickly put in place, or removed from, a service belt.

Further objects, advantages and capabilities will be apparent from the description and disclosure in the drawings, or may be comprehended or are inherent in the device.

In the drawings:

Figure 1 is a perspective view showing the attachment side of a holster made after the teachings of this present invention;

Figure 2 is a perspective view showing the holster attaching means in the open position, thus adapting it for easy attachment to a service belt;

Figure 3 is a perspective view showing the attachment flap in its using position but with the keeper not yet in position;

Figure 4 is a perspective view illustrating the preferably metal stape or D-ring assembly which is adapted to be secured to the holster proper;

Figure 5 is a fragmentary, perspective view, partly in section, illustrating an improved manner of finishing the upper portion of the holster and showing the fire-arm latch member in its using position;

Figure 6 is a perspective view cut by a longitudinal section illustrating the manner in which the latch member is constructed;

Figure 7 is a fragmentary perspective view, partly in section, illustrating the pistol-securing means, and to further illustrate how the attachment means can be effectively employed therewith;

Figure 8 is a fragmentary perspective view, partly in section, illustrating the resilient means which is used in association with the retaining latch illustrated in Figures 5 and 6; and

Figure 9 is an illustrative view showing the manner in which this present holster is preferably employed by its user.

Referring more particularly to the disclosure in the drawings, the holster body is formed preferably of a single piece of firm but yieldable material. In the past the better grades of leather have been extensively used. However, with the present high development in plastic materials, many of these inexpensive materials may be successfully used. The holster proper 10 is formed by molding a piece of yieldable sheet material back upon itself to form the two skirt portions 12 and 14. These portions are held in their desired position principally by molding, cementing and stitching at 16, 18, 26 and 28.

These stitched portions are of limited expanse due to the fact that in a "quick draw" holster of this order it is desirable that the gun removing side be largely open so as to not impede the movement of the gun and does not require that the same be raised upwardly appreciably in order to clear the holster. Following these principles it has been found desirable to employ a gun-retaining spring 20 which is formed to easily engage the firearm in the general vicinity of its balance which normally is just slightly in front of the trigger, or as illustrated in Figure 9, below the trigger toward the muzzle of the gun. Spring 20 must of course be adequately covered with protective sheet material as leather or the plastic material used in the holster, and to secure the spring firmly in position, a peripheral stitching 24 is provided.

The covered sheath 22 is illustrated in Figure 7 as being folded back to better illustrate the spring structure. It is shown further in its position of use in Figure 9, and it is held in place by marginal stitching as 26, 28.

In Figures 5 and 6 is illustrated a form of gun-securing latch which has been found to be a major improvement over the form shown in my former patent referred to previously. In this construction, a preferably plastic

molded member 30 is employed. This gives the required stiffness to the upper portion of the holster and provides a very secure anchorage for the metal latch member 32. This improved construction is probably best illustrated in Figure 6. In employing the plastic insert member 30, provision is made for the stitching 16 to pass through spaced openings 34 in the upper margin thereof so that the latch member itself is securely held in position; and possibly more important, is the fact that member 30 gives the required stiffness to the upper portion of the holster, in an economical manner, which insures its permanently retaining its desirable form.

Latch 32 coacts with the resilient spring structure 36, as illustrated in Figure 8, after the same principles employed in my former application, latch 32 engaging normally the hammer of the pistol in a manner to hold it against the gun tipping out of the open side of the holster. To release the gun from latch 32, the gun is pressed downwardly compressing spring 36 and thus freeing the gun for easy drawing.

The carrying of a pistol by the using personnel places a load on their belts around their waists that has always been objectionable. This is particularly true when the gun is of some weight, as it must be in order to provide for the safe handling of a cartridge of adequate power. It therefore becomes increasingly desirable that the user of the firearm can easily remove the same from his belt, holster and all, as even the holster is inconvenient and it interferes normally with one when he is seated. Then too the holster provides a case in effect for the protection of the weapon when it is desirable that it be removed from the belt at the time the gun is no longer needed. Military people and law enforcement officers usually find it necessary to have a number of items secured to their service belts. For the military, they may take the form of a first aid packet, extra magazines, or extra ammunition, and possibly encompass other impedimenta of that order. For the law enforcement officer, they usually entail a handcuff case, the extra ammunition, usually a blackjack or its equivalent, and quite often a first aid pack. With all this equipment secured to the belt it then becomes increasingly difficult to unthread anything from the belt and this is not desirable. It is to overcome this condition that I have provided a further useful addition in my holster in an improved holster securing means. This attachment is shown in greatest detail in Figures 1, 2, 3 and 4.

In Figure 1, which shows the side of the holster worn next to the body, the holster-securing flap 40 is provided. This flap normally is shaped after the illustrations so that it forms in effect a channel member, which should fit rather closely, the belt on which it is used. The flap is fixedly secured as by gluing and/or stitching at 42 so that the upper margin of the flap is at all times a part of the holster. At its lower margin, flap 40 is pierced with a plurality of elongated openings 44. These openings are of a form to coat with D-rings or staples 46 which may be individually affixed to the holster body 10, but are preferably fixedly secured as part of plate 48, which plate in turn is attached, as by rivets 50, or otherwise fixedly secured, to the body of the holster.

The manner in which this attachment means is employed is believed to be well illustrated throughout the various drawings. When the pistol is located on the belt after the showing of Figure 9, the flap 40 is engaged over staples 46 as illustrated in Figure 3, and then the leather thong keeper member 52, which is preferably secured to the flap as by cement and rivets and stitching 54, is passed through the plurality of staples 46 outside of flap 40 thus locking the flap in place. It is to be noted that it

is most convenient to provide the end of the keeper with a pointed portion as 56 preferably treated with a stiffening compound and to further provide an enlarged portion 58 in keeper 52 so that it will form a stop, after the showing of Figure 1. This arrangement will thus furnish a loop 60 so that when it is desired to remove the holster, the fingers can be engaged in loop 60 and a convenient releasing means is thus provided. The tip of the leather thong keeper is then inserted to the left of the last staple in back of the thong and pulled down after the showing of Figure 1, thus locking the thong and keeping the tip of the thong behind the holster.

It is believed, it will be clearly apparent from the above description and the disclosure in the drawings that the invention comprehends a novel construction of a belt-supported pistol holster.

Having thus disclosed the invention, I claim:

1. The improvement in a pistol holster to be worn on a belt, comprising: a holster housing having on its body abutting face a flap fixedly secured to the housing at the upper margin of the flap, said flap having near its lower edge a plurality of juxtaposed, spaced-apart slots and a metal plate riveted to said housing at the level of said slots having a plurality of D-rings formed thereon in position to be inserted in said slots, a thong-like keeper member secured at one end to said flap and having its other end portion tapered and treated with a stiffening agent and of a size so that it may be threaded through said D-rings when they are positioned in said slots to secure the flap in place and said keeper member having an enlarged intermediary portion limiting the extent of the keeper member which can be inserted in said D-rings so that a loop remains between the D-rings and the secured end of the keeper member engageable by the fingers for withdrawal of the keeper member to unfasten the flap, and said flap having a channel-like shape vertically intermediate its upper and lower edges of a size to accommodate such a belt.

2. The improvement in a pistol holster to be worn on a belt, comprising: a holster housing having on its body abutting face a flap fixedly secured to the housing at the upper margin of the flap; said flap having near its lower edge and spaced from said upper margin sufficient distance to contain such belt therebetween a plurality of juxtaposed, spaced-apart slots and a metal plate secured to said housing at the level of said slots having a plurality of D-rings formed thereon in position to be inserted in said slots; a thong-like keeper member secured at one end to said flap and having its other end portion threadable through said D-rings when they are positioned in said slots to secure to the flap in place and said keeper member having an enlarged intermediary portion limiting the extent of the keeper member which can be inserted in said D-rings so that a loop remains between the D-rings and the secured end of the keeper member engageable by the fingers for withdrawal of the keeper member to unfasten the flap.
